UNITED STATES PATENT OFFICE.

GIUSEPPE S. FALCONE AND JOSEPH N. FALCONE, OF HARTFORD, CONNECTICUT.

ARCH SUPPORTER FOR SHOES.

Application filed February 11, 1925. Serial No. 8,494.

This invention relates to arch supporters especially adapted for use in connection with shoes.

Briefly stated, an important object of the invention is to provide an arch supporter having a plurality of more or less separate sections which may be independently adjusted to conform to the curvature of one's foot.

10 Another important object of the invention is to provide an arch supporter which may be worn without discomfort and which will not in any way mar the appearance of the shoe.

15 Another object is to provide an arch supporter which is of highly simplified construction, durable in use, and inexpensive to manufacture.

20 Other objects and advantages of the invention will be apparent during the course of the following description.

In the accompanying drawing forming a part of this application and in which like numerals are employed to designate similar parts throughout the same,

25 Figure 1 is a side elevation of the improved arch supporter applied, the shoe being shown partly in section;

30 Fig. 2 is a perspective of the arch supporter detached;

Fig. 3 is a section on the line 3—3 of Fig. 2 and illustrating the adjusting means of one of the sections.

35 In the drawing, wherein for the purpose of illustration is shown a preferred embodiment of the invention, the numeral 5 generally designates a shoe having a heel 6 and inner and outer soles 7 and 8, respectively.

40 Coming now to the subject matter of the present invention and referring particularly to Figs. 1 and 2, it will be noted that the improved supporter which is preferably applied during the course of manufacture of the shoe is disposed between the inner and outer soles of the shoe and comprises a base plate 10 to which rear, intermediate, and front adjustable sections 12, 13 and 14, respectively, are secured.

45 The base plate 10 is constructed from suitably stout spring metal, such as steel or aluminum, and is curved longitudinally to conform generally to the arched or instep portion of the shoe and when in position will be flatly in contact with the upper surface 50 of the outer sole 8.

55 Mounted upon the upper face of the plate 10 are the adjustable sections 12, 13, and 14, one end portion of each of which is secured to the plate 10 as indicated at 15 by means of rivets, welding, or any other suitable means, 60 the other end of said sections being free so as to permit the sections to be raised or lowered independently of each other to provide the curvature desired to the inner sole 7. It will be seen that by having the sections separately and independently adjustable any one of the sections may be adjusted to provide the proper curvature to the instep of the shoe and thus furnish a convenient means whereby a particular portion 70 of the insole 7 may be raised or lowered so that the same will accurately conform to the shape of the instep of a particular individual.

Fig. 1 illustrates that screw bolts 16 are 75 threaded through the base plate 10 and contact with the free end portions of the spring members 12, 13 and 14. It is believed to be obvious that the adjustment of the screw bolts 16 will result in the movement of the members 12, 13 and 14 to the desired position. Particular attention is directed to the fact that the screw bolts 16 are extended through the outer sole and that the heads of the same are arranged exteriorly of 80 the shoe so that the heads may be quickly and conveniently engaged by a screw driver or other suitable tool employed in adjusting. When the screws are in their final positions the heads of the same are close to or are 85 embedded in the outer sole 8 so that the same will not cause the wearer of the shoe inconvenience or possibly cause the wearer to trip.

90 The members 12, 13 and 14 are in the nature of tongues or plates and with reference to Fig. 2 it will be seen that the intermediate plate 13 is provided with a laterally projecting portion which extends entirely across the intermediate portion of the base plate 10 100 and thereby presents an unbroken supporting surface for the center of the arch of the foot. The member 14 is arranged parallel and close to the member 13 and has its rear end cut away to allow for the laterally projecting portion of the member 13.

105 Particular attention is directed to Fig. 2 which plainly illustrates that the outer terminal portions of the spring tongues 12, 13 and 14 are rigidly connected to the base 110

plate 10 so that they are incapable of movement with respect to the base plate. That is to say, the terminal portions of the tongues 12, 13 and 14 cannot move with respect to the base plate and consequently the inner sole may not be pinched between the terminals of the base plate and the tongues. This also spaces the outer terminals of the spring tongues from wearing engagement with the outer sole as a result of flexing of the spring tongues.

From the foregoing it is believed to be plain that the improved arch supporter may be incorporated in the shoe either during manufacture or at any time thereafter. In any case the arch supporter is covered by the insole 7 so that a rather smooth contact surface is presented to the foot. The several members 12, 13 and 14 may be adjusted from time to time as the occasion requires and entirely independent of each other so that if the wearer finds that the supporter is arched more than is necessary, the screws 16 may be backed up to some extent to allow the spring members 12, 13 and 14 to recede.

Having thus described the invention, what is claimed is:

1. In combination with a shoe having an inner and outer sole, a base plate disposed between said inner and outer soles adjacent the instep portion, a plurality of separately adjustable arch supporting springs carried by said base plate, and adjusting means engaged with the terminals of said supporting springs and operable from the exterior of said shoe whereby the adjustable supports of said springs may be separately raised or lowered.

2. An arch supporter for use in shoes comprising a longitudinally curved base plate, a plurality of separate tongues of spring metal secured at their outer terminal portions to the base plate and having their inner terminal portions free, one of said tongues having a laterally projecting portion extending across the intermediate portion of said base plate and being positioned between the free inner ends of the other tongues, screw bolts threaded through said base plate and engaging the free end portions of said tongues whereby the tongues may be separately adjusted, said screw bolts being provided with heads adapted to be positioned exteriorly of the shoe.

3. An arch supporter comprising a longitudinally curved base plate adapted to be positioned within a shoe, a plurality of separate spring tongues rigidly connected at the outer terminal portions thereof to the base plate whereby the outer terminal portions of the spring tongues are incapable of movement with respect to the base plate, the inner terminal portions of the spring tongues being free, and adjusting devices threaded through said base plate and separately engaged with said spring tongues whereby the inner terminal portions of the spring tongues may be separately adjusted.

In testimony whereof we affix our signatures.

GIUSEPPE S. FALCONE.
JOSEPH N. FALCONE.
